UNITED STATES PATENT OFFICE.

WILLIAM TEDFORD ROGERS, OF KANSAS CITY, MISSOURI, ASSIGNOR OF ONE-HALF TO
VIRGIL R. WILKINSON, OF KANSAS CITY, MISSOURI.

CHANGEABLE SIGN.

1,362,542.

Specification of Letters Patent. Patented Dec. 14, 1920.

Application filed January 9, 1920. Serial No. 350,363.

To all whom it may concern:

Be it known that I, WILLIAM T. ROGERS, a citizen of the United States, and resident of Kansas City, county of Jackson, State of Missouri, have invented a certain new and useful Improvement in Changeable Signs, of which the following is a complete specification.

The present invention relates to sign construction, and aims to provide an improved device of the so called animated or changeable type of sign in which I provide various novel features both in the manner of mounting the different units of the sign and also in the manner of shifting these panels into their different display positions.

Accordingly I have devised an improved sign structure comprising a series of sign panels, together with mechanical operating means for shifting these panels in a predetermined order for displaying the same in different display positions which face in opposite directions, this mechanical means also operating to reverse each panel at the proper times for displaying both faces of the panel in each of the display positions.

In carrying out the invention, I provide a series of panels adapted to be moved in pairs into display positions, where they occupy a coplanar relation to each other, in which display position one of the pair of panels is caused to displace the other while moving into reverse position for displaying its opposite face, at which time also a third panel is brought into the position vacated by said reverse panel.

It is also sought to provide a construction of this character comprising units which can be multiplied to any desired extent, and without requiring any changes or alterations in the separate units for their joint assembly other than their connection with a joint driving mechanism.

A further object of the construction is to provide a device consisting of a plurality of movable sign panels so arranged and mounted as to enable the changes in the position of the panels to be made without requiring the use of panels limited to a relatively small size as has been the case heretofore.

Further features of improvement reside in a novel form of latching means for successively latching each unit of the device

in the various display positions thereof, and also in a special form of drive mechanism including means for intermittently releasing the latch mechanism between each shifting of the sign device.

With these and various other minor objects in view, the invention will now be described by reference to the accompanying drawings illustrating one form of construction which I have devised for embodying the proposed improvement, after which the novel features therein will be particularly set forth and claimed.

In the drawings—

Figure 1 is a side elevation partly broken away, showing a changeable sign device constructed in accordance with the present invention;

Fig. 2 is a plan view of the same, with the motor omitted;

Fig. 3 is an irregular sectional view, following in general the line 3—3 in Fig. 1, one pair of the sign panels' support being left in plan, with the panels omitted to show the manner of mounting the same;

Fig. 4 is a sectional view of one of the units of the device, being a section similar to that shown of the right unit in Fig. 3, but with the parts in shifted position;

Fig. 5 is a vertical section taken on the line 5—5 of Fig. 2;

Fig. 6 is a detailed section taken on the line 6—6 of Fig. 2; and

Fig. 7 is a diagrammatic view representing the various relatively different positions assumed by the different panels of each unit of the device, and following said changes through an entire cycle of the operation of such units.

Referring now to the drawings in detail, the improved construction is shown as comprising two changeable sign units mounted within one frame structure 8, and operated from a common drive mechanism, as illustrated in Figs. 1 and 2, and as each of said units is a duplicate of the other, the description will proceed with reference to one of the units with the understanding that the same reference characters apply to the corresponding parts of the other.

Each unit of the device comprises a plurality of sign panels 9, each of said panels being made in two sections mounted back to back upon a pivoted supporting bar 10

which is provided with notches 11 for engagement with the lower edges of the panel section. (See Fig. 3.) At their upper ends the sections of each panel 9 are secured together by means of screws 12 in engagement with lugs 13 depending from a pivoted bar 14, of a length approximately equal to the width of the panel. The upper pivoted bars 14 are pivotally connected at their mid points to pins 18 provided at the corners of a rectangular plate 16, which plate is fixed to a vertical shaft 17 supported in bushings 18 at the top and bottom of the frame 8. At the upper end of the shaft 17 is secured a spider frame 19, this frame being also of substantially rectangular form the same as the plate 16, this being in view of the fact that in the particular construction illustrated two pairs of sign panels comprise the total number of panels for each unit of the device. Accordingly the frame 19 is provided with an upwardly projecting stop pin 20 at each of its corners, one pin for each panel 9, these pins being adapted to be engaged by a latch member 21, pivoted at 22 to the frame 8 and provided with a spring 23 for actuating the latch into engagement with the several pins 20.

Driving mechanism is provided for intermittently tripping or releasing the latches 21 and imparting a partial rotation to each of the frames 19 and thereby rotating the shaft 17 for changing the positions of the sign panels in each unit. This drive mechanism comprises a motor 24 mounted upon a suitable shelf 25 over the framework 8, and driving a belt 26 which is trained over a groove wheel 27 on a shaft 28 journaled in a bearing frame 29 at one end of the frame 8. The shaft 28 is provided with a worm 30 meshing with a worm-wheel 31, which rotates on a vertical axis provided by a sub-shaft 32 projecting upwardly from the bearing frame 29. The wheel 31 is provided with a crank pin 33 for the application of a suitable connecting rod 34, the opposite end of which is fitted with a reduced end portion extending through a pivotal stud 35 carried by a pawl-carrying arm 36 which is journaled to the upper end of one of the shafts 17. The reduced end portion of the rod 34 is fitted with a coil spring 37 held in position by a cotter pin 38. This provides for a yielding actuation of the drive from the connecting rod 34, and permits the crank pin 33 to pass the center of the wheel 31 even in the event that this takes place at intervals subsequent to the springing of any one of the latches 21 into engagement with one of the pins 20. It is also pointed out that a friction drive is provided between the wheel 27 and its shaft 28, by interposing the coil spring 39 between said wheel and the frame 29; this character of drive will therefore act to relieve the load on the motor in

case of any accident to the sign parts or any obstruction to the changing movements of the sign to be hereinafter described.

The stud 35 is connected by a bar 40 with another stud 41 on the upper face of a second pawl-carrying arm 36 which is pivotally mounted upon the upper end of the other shaft 17, it being noted that said arms 36 are held yieldingly in engagement with the hub of the frame 19 by means of a coil spring 42 retained in place by means of a washer 43 and cotter 44.

Each of the arms 36 carries a pivoted pawl 45 (see Fig. 6) which is pivoted for free outward movement but for limited backward movement, whereby as the arms 36 swing backward over the pins 20, due to the reciprocation of the bar 40 by rod 34, the pawls 45 will ride idly over said pins 20, but on being advanced in the opposite direction by the arms 36 will engage said pins and thereby rotate the frames 19 and the shafts 17. Preliminarily, however, to each advanced movement of the arms 36 the latches 21 are tripped or released by the action of the pawls 45 in engaging an upwardly projecting flange 46 at the end of each latch 21, said flanges extending at an angle with reference to the direction of travel of the pawls 45 whereby the latches 21 obviously are crowded outward from engagement with the corresponding pins 20.

Means is provided for cooperation with the above described driving means for the purpose of both reversing each of the several panels and also shifting said panels back and forth from the two different display positions at the opposite sides of the frame 8, in which two display positions said panels are, obviously, displayed in oppositely facing directions. Each of the lower panel frames 10 is carried by a pin 50 which is journaled in one corner of a plate 51 secured to the corresponding shaft 17, as shown in Fig. 5. Below the plate 51 each pin 50 is secured to a bar 52 which is secured rigidly to the corresponding bottom frame 10 by means of posts 53, there being a pair of said posts 53 for each panel 9 and located at the same side of the pivot pin 50 for permitting the panel and the corresponding bar 52 to swing as one member about said pivot. At the opposite side of the pivot pin 50 each bar 52 is provided with a roller 54 which is obliged to follow a path in such a manner as to cause the sign panel to assume the various desired positions in accordance with the object of the invention. Accordingly a plate 55 is associated with each of the sets of rollers 54 and fixed to the frame 8 at the lower end of the shaft 17. This plate 55 is provided with angularly arranged side edges, as shown in Fig. 4 for the travel of the rollers 54 as the sign panels are shifted from one display to the opposite

display position. In the two display positions the plate 55 is also provided with channel passages 56, midway of which are provided recesses 57, for accommodating the rollers in the reversing movement of the panels, as also indicated in Fig. 4. The roller or channel passages 56 are formed with curved and peculiarly shaped outer walls 58 for effecting the alinement of each pair of panels as they arrive in either display position as well as also for initiating the reversing movement of said panels in each of said positions. For coöperating with the walls 58 and the recesses 57 in effecting the reversal of the panels a pair of posts 59 is provided for each of the recesses 57 between which posts the ends of the bars 10 are projected during the turning of the panel and thereby obliged to complete a full half turn before the corresponding roller 54 can continue its course through the passage 56. A preliminary directing movement is also imparted to each panel 9 and its roller 54 by means of a post 60, one of which posts 60 is provided at each end of a bar 61 extending obliquely of the frame and intersecting the shaft 17. As shown in Fig. 4 these posts 60 are carried in position for engaging the panels 9 outside the pivot pin 50 in such a manner as to throw the opposite sides of the panels inwardly and bring their rollers 54 out of the passages 56 toward the opposite side of the frame 8.

As shown in Fig. 1, a plurality of sign units of the character just described may be arranged for operation together, with the adjoining units displaying continuous reading matter, for which purpose the adjoining units coöperate in forming words or sentences, and if necessary the panels of each unit may be so decorated or lettered as to conjointly form a word or design. As represented in Fig. 1 the several panels of each unit of the device are consecutively brought by the described operating means into coplanar relation in the two different display positions at the opposite sides of the frame, said panels conjointly forming a word in each of the display positions. It is designed that each of the panels 9 be provided with display matter upon both of its opposite faces, the object being that each of said panels shall coöperate with both the preceding and the next following panels in forming the display matter exhibited by said panel in both positions for which purpose it is of course necessary to display both faces of each panel in each display position and also to shift said panels from one side to the other into each of said display positions.

Starting with the parts as illustrated in Fig. 2 for their initial position, the four panels of each unit are given a partial turn

by the above described operating means, the swinging taking place in the direction of the arrow as indicated in Fig. 4, which operation obviously results in transferring one of each pair of panels in one display position into the opposite display position on the other side of the frame 8. This is done, it will be understood, without reversing the panel's position, the movement of the same taking place bodily from one display position to the other, and displaying in the latter position the opposite face of the panel from that which was displayed in the first display position. At the same time the other panel of each pair is moved into the place vacated by the first panel but its position is reversed, due to a semi-rotation of said panel being effected by its roller 54 and the engagement of its bottom frame bar 10 between the corresponding posts 59 and the action of the outer wall 58 of the roller passage 56. The same operation takes place at both sides of the device, and is repeated for each successive operation of the drive mechanism. What takes place with reference to the change in the reading matter on the sign during the successive changes may be more readily understood by reference to the diagram outlined in Fig. 7 for the purpose of showing a set of four panels having each face thereof provided with reading matter or characters of such a nature as to read in conjunction with the characters appearing on both the preceding and succeeding panels. With each unit comprising four panels bearing characters on both faces as indicated in Fig. 7, it will be apparent that the four names or words formed by the several combinations of the different panels will be consecutively displayed in both of the display positions at the opposite sides of the device. In the example illustrated in Fig. 7, the panels are lettered to display consecutively the words "JOHN," "MARK," "SETH," and "FRED" and each of the panels bears on its opposite faces a portion of each of two of these words; for example, one of the panels bears the letters "SE" and the letters "RK" for displaying the names "SETH" and "MARK" respectively in coöperation with the next preceding and the next following panels. In the position illustrated at (a) in Fig. 7, the panel in question bearing the characters "SE" and "RK" forms the word "SETH" in conjunction with the preceding panel in one display position, while in the opposite display position the word "JOHN" is formed by the other two panels. Following the operation of the drive mechanism, the panel bearing the characters "SE" and "RK" is transferred to the opposite display position as illustrated at (b) in Fig. 7, where it displays the characters "RK" for exhibiting, in conjunction with the other

panel in that display position, the word "MARK". In the other display position, however, the preceding panel has been reversed in position to display the characters 5 "FR", and producing the word "FRED" in that display position. In the next operation the panel just referred to as having been reversed is likewise transferred into the other display position, where it again 10 operates with the preceding panel to exhibit the word "SETH" in the second display position. Similar operations occur with reference to all four panels of the series, with the result that all four words possible 15 with the combinations afforded by said panels are exhibited consecutively in each of the two different display positions as will be readily understood by inspection of Fig. 7, illustrating the complete cycle of operation for one unit of the device.

It is furthermore apparent, on following the successive movements of the panels as partially indicated in Fig. 4 that clearance 20 has to be provided between the pins 60 and 25 the shaft 17 for only that portion of the panel which is provided with the roller 54 and that consequently the portion of the panel between its outer edge and the pivot 50 may be made of any width desired, this 30 being due to the fact that, in general, the movement of the panel in being shifted from place to place upon the shaft 17 takes place with its side carrying the roller 54 maintained practically constantly in position 35 between the shaft 17 and the pivot 50 of the panel. Thus no limit whatever is required as to the size, i. e. the width of the panel and this may be made of any extent desired. It is also obvious that the number 40 of units or individual assemblies of panels may be multiplied to any desired extent, as for forming a bill board of any considerable size, all of the units being actuated by a common drive mechanism. In this connection it may also be pointed out that the 45 number of panels comprising each of the units or assemblies about any one axis or shaft 17 may also be any number desired provided it be an even number of sections 50 or panels. For example, in place of the four panels operating as shown, with each operation resulting in the transfer of a panel from each display position indirectly into the opposite display position, the construction 55 may be amplified by the introduction of intermediate panels between the two display positions in the operation of which the transfer of a panel from a display position in the direction of the opposite display 60 position will result in such panel passing through an intermediate inoperative position prior to its later movement into its second display position; the remaining features of the operation would of course re- 65 main the same, this increase in the number

of panels simply providing for additional advertising matter with corresponding increase in the capacity and usefulness of the device.

It will thus be apparent that I have provided an efficient and comparatively simple construction and arrangement for embodying the proposed features of improvement, and while I have illustrated what I now regard as the preferred form of construction, I desire to especially reserve the right to make such changes and modifications as may fairly fall within the scope of the following claims.

What I claim is:

1. A changeable sign comprising a supporting structure, a movable panel carried by said structure and movable bodily with reference thereto, said panel being pivoted for rotary movement independent of the bodily movement of the panel, and means for bodily shifting said panel from one position into another position displaced from and adjoining its first position and in the same plane while simultaneously producing a semi-rotation of the panel about its pivotal axis for reversing the panel.

2. A changeable sign comprising a supporting structure, a pair of movable panels carried by said structure and movable bodily with reference thereto, said panels being separately pivoted for individual rotary movement independent of the bodily movement of the panels, and means for moving said panels into coplanar relation, said means operating thereafter to displace one of said panels with the other panel with the latter in reversed position.

3. A changeable sign comprising a supporting structure providing display positions facing in opposite directions, a pair of movable panels carried by said structure, in coplanar relation in each of said positions, and means operating to shift one panel of each pair from one to the other of said display positions and displaying different faces of said panels in the different positions, said means acting further to reverse the other panel of each pair and move the same into the position vacated by its companion panel.

4. A changeable sign comprising a supporting structure providing display positions facing in opposite directions, a movable panel carried by said structure, and means operating to shift said panel by moving the same bodily backward from one display position into the other display position parallel to the first, said means acting to present the opposite faces of said panel in said first and second positions, respectively.

5. A changeable sign comprising a supporting structure, a plurality of movable panels carried by said structure, and means for moving a pair of said panels into coplanar relation, said means operating there-

after to displace one of said pair of panels with the other of said pair, with the latter panel in reversed position and simultaneously moving another panel into coplanar relation with said reversed panel.

6. A changeable sign comprising a supporting structure providing display positions facing in opposite directions, a plurality of movable panels carried by said structure, means of removing a pair of said panels into coplanar relation in each of said positions, said means operating further to simultaneously displace one panel of each pair with its companion panel with the latter in reversed position, while simultaneously moving other panels into the positions vacated by said reversed panels.

7. A changeable sign comprising a supporting structure providing separate and spaced display positions facing in opposite directions, a movable panel carried by said structure, means for bodily moving said panel successively from one of said display positions to the other and acting to reverse said panel while occupying each of said positions and between the successive bodily movements of the panel.

8. A changeable sign comprising a supporting structure providing display positions facing in opposite directions; a plurality of panels carried by said structure and moving in a series successively into said display positions with a pair of said panels conjointly occupying said positions at intervals, and means for intermittently removing one of the panels from each of said positions and simultaneously reversing and shifting the other panel of that pair in place of the removed panels, said means acting further to replace said reversed panels with other panels of the series.

9. A changeable sign comprising a rotating member carrying independently pivoted sign panels, means for intermittently rotating said member for successively displaying said panels in oppositely facing directions, and means for intermittently latching said member during the display intervals of said panels, said rotating means operating to trip said latching means for permitting rotary movement of said member.

In witness whereof I affix my signature.

WILLIAM TEDFORD ROGERS.
